TYPOGRAPHICAL MOLD AND SLUG

Edward M. Righter, Lincoln, Nebr., assignor to
Intertype Corporation, Brooklyn, N. Y., a corporation of New York

Application June 5, 1937, Serial No. 146,665

25 Claims. (CL. 199—57)

The present invention relates to improvements in molds of the class having a slot therein for casting character bearing type bars or slugs, and it relates more particularly to molds of the kind employed in typographical line casting machines of the general class shown and described in U. S. Letters Patent No. 436,532 granted September 16, 1890 in which lines of character bearing matrices are presented to the mold and against which the type bars or slugs are cast.

Modern machines of this class are usually provided with four molds in which the length of the casting slot may be varied to enable the casting of slugs of different lengths to suit different column widths, and in which the height of the slot may be varied to produce slugs of different thicknesses to suit type characters of different point sizes. However, once the slot in the mold is adjusted to a given length or height the mold is capable of producing at each casting operation only one slug of corresponding size. Special molds have been proposed for producing more than one slug at each casting operation but such molds are seldom used since the several slugs, all of the same point size were cast separately from one another, that is, in separated portions of the casting slot, thus requiring special ejecting mechanism arranged to penetrate each separate portion of the casting slot and special slug guiding mechanism arranged to carry the several separate slugs to proper points of assembly on the usual galley.

The primary object of the present invention, in its broad aspect, is to increase the slug casting capacity of the total number of molds that may be present on the machine whereby without exchanging or adjusting these molds they will be capable of producing a greater number of slugs of the same or of different point size.

More particularly, the object of the present invention is to provide a single mold capable of producing as one composite slug a plurality of slugs of the same or of different lengths or point sizes. More specifically, the invention provides a mold having a longitudinal casting slot which is continuous in that it comprises at least two distinct but communicating portions of the same or of different lengths or point sizes, and having the end walls adjacent to the communicating passages between the several portions along the casting slot perpendicular to the longitudinal walls of the slot. With this arrangement slugs cast in each portion at each casting operation will be joined together and may therefore be ejected as a single composite slug by the usual

ejecting mechanism employed in machines of this class, guided in the usual manner to the galley without requiring alteration of the latter, and the several slug sections subsequently separated from one another by breaking or by sawing them apart. After being separated the ends of the several slug sections will be square with the side faces as required in order that the slugs can be properly assembled in the printing forms in which they are used.

A mold having these characteristics possesses many advantages over molds of this class as heretofore used, as will be apparent to those skilled in the art. For example, in newspaper composition, a single mold according to the present invention and provided with two casting slots of different point sizes may be used for the production of the slugs of column width for text lines in the slot of smaller point size, and for the production of the slugs of like width for headings in the slot of larger point size. Also in casting slugs with overhanging characters, both the useful or character bearing slug and the required underlay may be cast and ejected at the same time from one mold instead of requiring the use of two molds, as heretofore. Furthermore, in certain forms of logotype or tabular composition the several slugs required may be cast in one operation and then ejected and separated.

To these and other ends, the invention consists in certain improvements and combinations and arrangements of parts all as will be hereinafter set forth, the features of novelty being pointed out more particularly in the claims at the end of this specification.

In the accompanying drawings:—

Figure 1 is a front elevation of a portion of the usual mold disk of a typographical machine of the class hereinbefore referred to, having a mold according to the present invention mounted thereon;

Figure 2 is a vertical section through the mold disk, taken on the line 2—2 in Fig. 1, and showing a matrix line presented to the mold;

Figure 3 is a section through the mold and mold disk, taken on the line 3—3 in Fig. 1, showing one of the usual vise jaws cooperating with the mold;

Figure 4 is a detailed perspective view of the form of dividing member shown in Fig. 1;

Figure 5 is a side elevation of one well known form of slug ejector, showing the relation thereof to the mold according to the present invention;

Figure 6 is a perspective view of a slug cast

in the mold shown in Fig. 1 when the matrix line is presented to the left hand portion of the casting slot;

Figure 7 is a view similar to Fig. 6 but shows 5 the slug after the useful or character bearing portion thereof has been separated from the other or useless portion;

Figure 8 is a view similar to Fig. 3 but shows 10 the cast matrix character of a size larger than the point size of the mold slot so that the character overhangs the body of the cast slug;

Figure 9 is a front elevation of a slug such as may be produced in the mold shown in Fig. 8;

Figures 9^a and 9^b are end elevations of the slug 15 shown in Fig. 9 as viewed respectively from the left hand and right hand ends thereof, the underlay slug being applied to the character bearing slug;

Fig. 10 is a front elevation of a slug cast in 20 the mold shown in Fig. 1 when the matrix line is presented to the right hand portion of the casting slot;

Figure 11 is a front elevation of the mold shown in section in Fig. 8 and shows the casting 25 slot comprising two communicating portions of equal height and length for simultaneously producing the slugs in Figs. 9, 9^a, and 9^b;

Figure 12 is a front elevation similar to Fig. 1 30 but shows the casting slot comprising three communicating portions of unequal length;

Figure 13 is a front elevation showing the composite slug cast in the mold in Fig. 12 after 35 ejection; and

Figure 14 is a view of the slug cast as shown in 40 Fig. 13 after the sections thereof have been broken apart and the square ends of two of the sections butted together.

Similar parts are designated by the same reference characters in the different figures.

40 In the present instance, the mold according to the present invention is shown applied to a machine of usual well known construction in which several molds are mounted on the well known rotary mold wheel or disk 1 and secured thereto by bolts 2, the mold disk shown having a capacity of four molds. For convenience, the invention is illustrated as applied to a well known form of mold which comprises an upper or cap section 3 and a lower or body section 4, the inner opposed faces of these mold sections, when clamped together against so-called liners 5 and 6 at opposite ends, defining the longitudinal walls of the casting slot the length of which is determined by the location of the inner ends of the 55 respective liners.

Heretofore, the casting slot in molds of this class has ordinarily been made continuous and of uniform height or point size over its entire length between the inner ends of the opposed 60 liners, and the casting face of the cap section has been formed either with a smooth surface throughout its entire length for casting solid body slugs in the smaller point sizes or with a transversely recessed surface throughout the 65 length of the slot for casting skeleton body slugs in the larger point sizes. The mold according to the present invention differs from such conventional mold construction in that the casting slot is of the same or of different point sizes for different portions of its length, but the different portions of the casting slot communicate with one another through a passage of less height than that of either of said portions, and the end walls in each portion, so far as they exist above the 70 75 passage, are perpendicular to the longitudinal

walls of the casting slot. Furthermore, according to the present invention, the cap section may be alike for each portion of the casting slot, either recessed or plain, or the cap section may be recessed for one slot portion and plain for the other 8 slot portion.

According to one embodiment of the invention shown in Fig. 1, the mold cap 3 differs from the usual mold construction in that it is provided with a smooth casting face 7 along the right hand portion of its length and is provided with a recessed casting face 8 along the left hand portion of its length, the height of the right hand end of the casting slot differing from that of the left hand end thereof, as indicated by the difference 15 in the distances of the cap surfaces 7 and 8 respectively from the opposed casting surface of the mold body 4.

The casting slot is continuous from the inner end of the liner 5 to the inner end of the liner 6, 20 the portions 9^a and 9^b of the slot which are of different heights or point sizes communicating with each other through a portion 10 which is preferably of less height than either of the portions 9^a and 9^b of the slot and is formed by a 25 dividing member 12 which extends transversely across the casting slot and is secured preferably to the cap section 3 as by a dovetail rib or joint 13. The member 12 is provided with ribs 14 along both of its sides, these ribs extending 30 transversely across and projecting into the casting slot to within a short distance above the casting face of the mold body 4. The portion 10 of the casting slot opposite to the member 12 is thus reduced in height by said member to a height 35 less than the height or point size of both of the portions 9^a and 9^b of the casting slot. A further feature of the dividing member 12 is that its outer edges 12^a provide end walls adjacent to the communicating passage 10 which are perpendicular 40 to the upper and lower longitudinal walls of the several slot portions.

The portions 9^a and 9^b thus constitute in effect two communicating slug casting slots of different heights or point sizes, and end walls which 45 are square with the longitudinal walls of the slots but fall slightly short of the full heights thereof. The slugs cast in these slots will be joined together as a composite single slug by the short section of the slug which will be cast in the communicating portion 10 between such slots. Fig. 6 shows the composite slug as ejected from the mold by the blade 11 of the usual slug ejecting mechanism shown in Fig. 5, the section 15 of the slug having been cast in the slot 9^a and the section 16 cast in the slot 9^b, these sections of the slug 50 being joined together by the short connecting section 17 cast in the communicating portion opposite to the dividing member 12.

Due to the projecting of the ribs 14 on the 60 member 12 into the mold slot, the actual connection of the slug sections 15 and 16 with the section 17 is relatively thin and therefore so weak that the slug sections 16 and 17 may be easily detached from the section 17 merely by breaking 65 them off. Fig. 7 shows the slug section 16 detached in that manner and it is to be noted that apart from the slight irregularity of the broken areas the ends of both of the slug sections 15 and 16, due to the walls 12^a, are of the usual 70 formation, that is smooth and perpendicular to the longitudinal sides of the slugs. Obviously, the member 12 may be of any suitable length in the direction of the length of the casting slot and one or more of such members may be provided 75

at any desired points along the slot. Furthermore, the member 12 and the dovetail slot to receive it might be omitted entirely with the result that the composite slug would then comprise the slug sections 15 and 16 of different point sizes immediately adjoining one another and which, subsequent to ejection from the mold, could be detached by sawing. Moreover, should it be desired to provide the machine with a special ejector mechanism, a member 12 may be employed which will completely isolate or separate the two different point size portions of the slot from one another.

The mold as shown and herein described may be used with ordinary matrices presented to either of the two different point size portions of the slot. For example, to produce the slug shown in Fig. 6, a line is composed comprising sufficient character matrices 18 (Fig. 2) to suit the length of the slot portion 9^b and the remainder of the line is filled out with blank matrices to close the remainder of the slot up to the liner 5, or the slug shown in Fig. 10 may be cast from a line comprising blank matrices at the beginning of the slot portion 9^b and up to the left hand end of the slot portion 9^a, and character bearing matrices at the right hand end of the line where they will be presented to the slot portion 9^a, the slug then cast in the mold comprising the character bearing section 15^a of one point size, a non-character bearing section 16^a of a different point size and an intermediate connecting section 17^a. It will be understood of course that instead of employing blank matrices to fill out the line to the proper length beyond the character bearing matrices at either end, any of the so-called "quadding" attachments now available on commercial machines will serve to move one or the other of the usual vise jaws, one of which is designated 19 in Fig. 3, to close the mold at the front over the extent of the casting slot not occupied by the character bearing matrices and thus enable slugs of the kinds shown in Figs. 6 and 10 to be cast without the use of blank matrices.

Although the two communicating portions 9^a and 9^b of the casting slot in the mold shown in Fig. 1 are of different point sizes and differ also as to the casting faces of the mold cap 3, it is to be understood that both portions of the slot may be of the same point size and may be alike as to the formation of the cap section 3 for each portion of the mold slot, a substantial advantage of the present invention being that it enables a single mold to produce connected slugs in the same or different point sizes at each casting operation which slugs may be easily separated subsequent to ejection from the mold and have their ends formed perpendicular to their sides as usual.

The improved mold according to the present invention may also be employed for the casting of a composite slug comprising sections one of which bears overhanging characters and the other section of which is plain and of the proper thickness and length to be employed as an underlay for the overlying characters, as shown in Figs. 9, 9^a, and 9^b. In casting such a slug, matrices 18, as shown in Fig. 8 are employed, these matrices being provided with characters 18^a which are of larger point size than that of the portion of the casting slot to which they are presented, and for purposes of illustration of this embodiment of the invention, it may be assumed that the mold as shown in Fig. 11 is provided with two communicating slot portions 20^a and 22^a

of equal length and point size, both slots also having smooth walls like the slot portion 9^a in the mold in Fig. 1. It will be understood, however, that while it is preferable in this instance to have slot sections of equal length, the height or point size of the respective sections may differ, the only point of importance being that the section for producing the underlay slug be at least equal in point size to the amount by which the characters overhang the body of the character bearing slug.

The composite slug resulting from use of the mold shown in Figs. 8 and 11 will comprise a character bearing section 20 having the characters 21 overhanging the body portion of the slug section at one side, the character bearing section 20 being connected by a portion like the portion 17 in Fig. 6 to a blank section 22 of the same length and point size as the slug section 20. After ejection of such a composite slug from the mold, the slug sections 20 and 22 may be broken off from the connecting portion and as heretofore explained the opposite ends of the two slug sections which are cast against the walls 12^a will be square with the sides of the slug sections. Since the characters 21 on the slug section 20 overhang the body of this slug section which is of a smaller point size than that of the characters, it will be seen that the blank slug section 22, when placed against the side of the slug section 20 from which the characters project, will be of the proper length and thickness to serve as an underlay or support for the overhanging characters 21. Figure 9^a shows the slug section 22 laid on the character bearing slug section 20, as viewed from the left hand end of Fig. 9, 22^b representing the portion of reduced thickness which connects the section 22 to the intermediate section 17 and at which point these slug sections are broken apart or otherwise separated, and Fig. 9^b shows the slug sections 20 and 22 assembled and as viewed from the right in Fig. 9, 20^b representing the portion of reduced thickness which connects the slug section 20 to the intermediate portion 17 and from which it has been broken off or otherwise separated. The present invention thus enables a single mold to produce, at one casting operation, a slug with overhanging characters and, connected to and ejected with such a slug, a blank slug of the proper length and thickness to serve as the required underlay, without requiring two molds as heretofore.

The mold in Fig. 12 shows another embodiment of the invention wherein the casting slot comprises three communicating slot portions 23, 23^a, and 23^b of equal height but each of a different length, these slot portions being formed by two dividing members 24. The dividing members 24 serve the same general purpose as the dividing member 12, the only difference being in the formation of the ribs 25 on the members 24 wherein these ribs project slightly beyond the vertical sides 26 of the members 24 along the extreme lower edge of said sides. The object of this outward projecting edge is that the section of reduced thickness for facilitating the breaking apart of the several slugs will always lie slightly back of the square ends of the slugs.

Such construction has the advantage of assuring that whatever irregularities exist due to breaking the slug sections apart will be located back of the square ends cast against the vertical portions of the sides of the members 24. Thus, the slug sections can be tightly and squarely butted against one another or against slugs cast

in standard molds or against rules, blocks or the like with which they are associated in well known manner when assembled into printing forms. Fig. 13 shows the slug as cast in the mold shown in Fig. 12, and Fig. 14 shows two of the slug sections 23' and 23'' after being broken apart and their square ends butted together.

I claim as my invention:

1. A mold for a slug casting machine having 10 non-adjacent longitudinal casting slots of different heights and a communicating passage between the slots of less height than either of said slots.
2. A mold for a slug casting machine having 15 a longitudinal casting slot recessed over a portion of its length to cast a slug of a given point size and non-recessed over another portion of its length to cast a slug of a different point size, and an intermediate passage communicating with 20 the recessed and non-recessed portions of the casting slot to cast a section of less thickness than either of the slugs cast in said slot portions and adjoined at its opposed ends with said slugs.
3. A mold for a slug casting machine having a 25 longitudinal casting slot comprising a plurality of rectangular casting cavities for casting different slugs and means extending laterally between said cavities for casting portions of relatively reduced thickness connecting the different 30 slugs together.
4. A mold for a slug casting machine having a longitudinal casting slot comprising at least two casting cavities with end walls perpendicular to the longitudinal walls of the slot, the adjacent 35 end walls between said cavities extending over a portion only of the height of said slot to thereby provide a communicating passage between said cavities.
5. A mold for a slug casting machine having a 40 longitudinal casting slot comprising a plurality of non-adjacent casting cavities of different lengths for casting rectangular slugs of different lengths and means between said cavities for casting portions connecting the slugs together along a portion only of their opposed ends.
6. A mold for a slug casting machine having a 45 longitudinal casting slot comprising a plurality of casting cavities of rectangular form but differing from one another in height and means between the cavities forming the adjacent end walls thereof and a communicating passage of less height than either of said cavities.
7. A mold for a slug casting machine having a 50 longitudinal casting slot and a member extending transversely through and partially across the height of the slot for forming by its opposed sides the adjacent end walls of a plurality of communicating casting cavities of rectangular form, said member along the extremity of its 55 projection into the casting slot having transverse ribs projecting outwardly from its opposed sides.
8. A mold for a slug casting machine having a 60 continuous longitudinal casting slot and a slot dividing member projecting from one of the longitudinal walls toward the opposed wall; said member forming by its opposed sides the adjacent end walls of different rectangular casting cavities and forming by the extremity of its projecting edge a passage between said cavities of greater length 65 than the distance between the end walls formed by its opposed sides.
9. A mold for a slug casting machine having a longitudinal casting slot comprising portions of different heights and a transverse member 70 providing a communicating passage between said 75

portions and defining by its opposed sides the adjacent end walls of said slot portions.

10. A mold for a slug casting machine having a casting slot comprising longitudinal end portions of different heights for casting slugs of 5 different thicknesses and an intermediate portion of less height than said end portions for casting a connecting portion of less thickness than said slugs.

11. A mold for a slug casting machine having 10 a casting slot comprising longitudinal end portions of different heights and a dividing member providing an intermediate connecting portion of less height than said end portions and having a rib extending transversely of the slot and projecting perpendicularly from one longitudinal wall toward the other wall thereof. 15

12. A mold for a slug casting machine having a casting slot of different heights towards its ends to cast slugs of different thicknesses, and having a 20 member projecting partially across said slot 25 intermediately of its ends for casting a connecting portion of reduced thickness.

13. A mold for a slug casting machine having a longitudinal casting slot comprising portions 25 of different heights toward its ends, one of said portions being recessed and the other non-recessed, and a dividing member located between said portions and providing a communicating passage of reduced height, said member having 30 ribs thereon extending transversely of the slot and projecting partially across the height thereof.

14. A mold for a slug casting machine having a continuous longitudinal casting slot of a height toward one end to cast a slug with characters 35 overhanging a side thereof, and having a height toward its other end equal to the amount of overhang of said characters from the first mentioned slug.

15. A typographical slug comprising slug sections of equal height but different thicknesses, 40 said sections being of different point sizes and adjoined to one another endwise.

16. A composite typographical slug comprising end sections of different thicknesses and an intermediate portion of less thickness than either of 45 said end sections.

17. A typographical slug comprising rectangular longitudinally extending end sections of 50 equal height and uniform in height throughout their lengths, one of which sections is ribbed and the other plain and of relatively less thickness, and a lateral connecting portion as the same height as the end portions but of less thickness than either of said portions.

18. A typographical slug comprising end sections one of which bears overhanging characters and the other being plain and of a thickness equal to the extent of overhang of said characters, said sections being connected separably by 60 an intermediate portion.

19. A composite typographical slug comprising a plurality of rectangular slug sections of a given thickness and portions connecting the sections together along a portion only of the area of their 65 adjacent ends.

20. A composite typographical slug comprising at least two slug sections of rectangular form, and an intermediate portion joining the slug sections together by a separable connection located back of the adjacent ends of said slug sections. 70

21. A composite typographical slug comprising at least two slug sections having parallel side faces and end faces perpendicular thereto, and a 75

connecting portion intermediate of the end faces, said connecting portion being of less thickness than the distance between the side faces of the slug sections and lying in the plane of one of said side faces.

5 22. A mold for a slug casting machine having non-adjacent longitudinal casting slots each of the full lateral depth of the mold but of different height along different portions of the length of 10 the mold and a communicating passage between said casting slots.

10 23. A mold for a slug casting machine having communicating longitudinal casting slots of equal depth laterally, one of said slots being recessed 15 to a given point size and the other slot being plain and of a different point size for producing connected plain and recessed slugs correspondingly differing in point size.

24. A mold for a slug casting machine having communicating longitudinal casting slots of equal depth laterally throughout their length, one of said slots being recessed and the other plain for producing a composite slug having correspondingly plain and recessed portions.

5 25. A mold for a slug casting machine having non-adjacent longitudinal casting slots one of which is recessed to cast a slug with portions alternating over its length between two different 10 point sizes and the other of which is non-recessed to cast a slug of only one point size throughout its length, and an intermediate passage connecting the recessed and non-recessed casting slots to cast a section of less thickness than either of 15 the slugs cast in said slots and adjoined at its opposite ends with said slugs.

EDWARD M. RIGHTER.
